(57) **CLAIM**

We claim the ornamental design for a trimmer line winding package, as shown and described.

DESCRIPTION

FIG. 1 is a right perspective view of the trimmer line winding package;

FIG. 2 is a front view of the trimmer line winding package shown in FIG. 1;

FIG. 3 is a rear view of the trimmer line winding package shown in FIG. 1;

FIG. 4 is a left side profile view of the trimmer line winding package shown in FIG. 1;

FIG. 5 is a right side profile view of the trimmer line winding package shown in FIG. 1;

FIG. 6 is a top view of the trimmer line winding package shown in FIG. 1; and,

FIG. 7 is a bottom view of the trimmer line winding package shown in FIG. 1.

In the drawings, the broken lines depict unclaimed subject matter only and form no part of the claimed design.
